UNITED STATES PATENT OFFICE.

EDWARD N. TRUMP, OF SYRACUSE, NEW YORK.

LIXIVIATING APPARATUS.

No. 889,159.

Specification of Letters Patent.

Patented May 26, 1908.

Application filed August 26, 1897, Serial No. 649,575. Renewed October 12, 1907. Serial No. 397,167.

To all whom it may concern:

Be it known that I, EDWARD N. TRUMP, of Syracuse, in the county of Onondaga, in the State of New York, have invented new and 5 useful Improvements in Lixiviating Apparatus, of which the following, taken in connection with the accompanying drawing, is a full, clear, and exact description.

My invention relates to improvements in 10 lixiviating apparatus, and has for its object the production of a device which is simple in construction, continuous in operation, highly efficient in use, and requires a minimum amount of attention; and to this end, the 15 invention consists in the combination, construction, and arrangement of the component parts of a lixiviating apparatus, all as hereinafter fully described and pointed out in the claims.

20 In describing this invention, reference is had to the accompanying drawing, forming a part of this specification, in which like letters indicate corresponding parts in all the views.

25 Figure 1 is a longitudinal vertical section, partly in elevation, of my improved lixiviating apparatus. Figs. 2, 3 and 4 are transverse vertical sections, taken, respectively, on lines 2—2, 3—3, and 4—4, Fig. 1. Figs. 30 5 and 6 are transverse vertical sections, looking in opposite directions, taken on line 5—6, Fig. 1; and Fig. 7 is a longitudinal vertical section, partly in elevation, of a modified construction of my improved lixiviating apparatus.

35 As usually constructed, a lixiviating apparatus consists of a number of fixed chambers or receptacles, conduits or pipes for connecting the chambers or receptacles in different series or batteries, and supply-conduits or pipes for conducting the soluble material and the dissolvent liquid, respectively, to the first and last chambers or receptacles of the various series of batteries. A lixiviating apparatus of this construction requires considerable attention, and the lixiviation effected thereby is more or less un-uniform, owing to the variation in the connection of the different chambers or receptacles. My present 45 invention is radically different from such apparatus, since the dissolvent liquid and the soluble material are continuously fed therethrough in opposite directions without liability of variation in the process or the necessity of rearrangement of the component parts of the apparatus.

4 A is the inclosing shell of my improved lixiviating apparatus, *a a*, a series of compartments arranged within the inclosing shell, and B, C inlet-conduits or pipes for feeding the soluble material and the dissolvent liquid. The shell A preferably consists of a revoluble cylinder which is usually supported in an inclined plane, and the compartments *a a* are generally inclosed between the 65 lower portions of the convolutions of a spirally arranged conveyer-blade *a'* which is fixed to the inner face of said shell and changes the position of said compartments as the shell A is revolved.

70 The inlet-conduit or pipe B for the soluble material preferably discharges into the lower end of the shell A and the material discharged from said conduit or pipe is fed lengthwise of the shell A by the conveyer-blade *a'*. Said inlet-conduit or pipe is usually formed with an enlarged flaring upper extremity, and is mounted upon a suitable support. As here illustrated, the support for the conduit or pipe B consists of a stationary chamber D 75 which is provided with an outlet-pipe or conduit *d* and communicates with the shell A for receiving the solution of the dissolvent liquid and the soluble material.

75 The inlet-conduit or pipe C for the dissolvent liquid usually discharges into the upper end of the shell A and preferably extends longitudinally within said shell for a considerable distance. Said conduit or pipe C may be held in position by any suitable support *C'* 80 and may be supplied with steam or other heating fluid by a conduit or pipe *C''*. The dissolvent liquid supplied by the conduit or pipe *C* feeds through the shell A in a direction opposite to that of the soluble material discharged into said shell by the inlet-conduit or pipe B. Said dissolvent liquid preferably 85 overflows from the uppermost compartment *a* to which it is supplied and feeds by gravity to the next lower compartment *a*, and continues its downward passage from one compartment to another, until it escapes from the lower end of the shell A into the chamber D. It is obvious, however, that the conveyer-blade *a'* may be perforated to permit 90

95 the passage of the dissolvent liquid therethrough, and in that event, the shell for receiving said liquid and the soluble material may be arranged in a substantially horizontal plane.

100 The revoluble movement of the shell A 105 may be effected by any suitable actuating

means, and I have here shown said shell as provided with a peripheral gear A' which is engaged by a driving gear, not illustrated. The friction incidental to the revolution of the shell A is preferably reduced to a minimum by suitable rollers A² which support said shell. These rollers engage projecting tires A³ upon the shell A and are preferably mounted upon the upper and lower ends of 10 rock-arms A⁴ A⁴ which are usually arranged on opposite sides of a vertical plane projected through the axis of the shell A. The intermediate portions of the rock-arms are pivoted or journaled in supports A⁵ which are 15 adjustable towards and away from each other by suitable bolts A⁶ and are held in position by suitable fastening means A⁷.

The undissolved material fed upwardly by 20 the conveyer-blade a' is discharged into a suitable receptacle or chamber whence it may be removed by any desirable means. In the 25 preferable construction of my invention, said material is discharged into the lower end of an inclined cylindrical receptacle or chamber E which usually projects within the upper 30 end of the shell A and revolves therewith. A portion of the inclosing wall of the receptacle or chamber E is generally perforated for permitting the escape into the shell A of any 35 liquid and small particles of undissolved material admitted to said receptacle or chamber. The undissolved material discharged into the receptacle or chamber E and not escaping through the perforations in its inclosing wall 40 is fed upwardly through said receptacle or chamber by any suitable feeding means, as a spiral conveyer-blade e, and is discharged from the upper end of the receptacle or chamber E to the exterior of the shell A.

45 The inlet-conduit or pipe C preferably extends longitudinally within the receptacle or chamber E and discharges the strong or fresh dissolvent liquid upon the undissolved material, and the perforations in said receptacle or chamber permit the ready escape of said 50 strong or fresh dissolvent liquid into the inclosing shell A, whence it passes from one compartment to another in a direction opposite to that of the material fed by the conveyer-blade a'. The dissolvent liquid escaping from the receptacle or chamber E facilitates the outward passage of small particles of undissolved material through the perforations in the inclosing wall of said receptacle or chamber, and said particles are fed 55 downwardly towards the conduit or pipe B by a suitable spiral conveyer-blade a⁷ which is usually arranged within the upper end of the shell A at the exterior of the receptacle or chamber E and is inclined in a direction opposite to that of the conveyer-blade a'.

60 Any suitable means may be used for feeding the undissolved material from the inclosing shell A into the chamber or receptacle E, and I have illustrated for such pur-

pose, a feeding chamber F, a pocket or scoop f, and an opening e¹ in the receptacle or chamber E. The feeding chamber F usually encircles the lower or inner end of the receptacle or chamber E and is inclosed between adjacent portions of the inner face of the shell A, the periphery of the receptacle or chamber E and substantially parallel circular shoulders or flanges f¹ f² interposed between said faces. The shoulders or flanges f¹ f² are formed with openings f³ which 70 facilitate the onward passage of the dissolvent liquid through the chamber E, and additional openings f⁴ f⁵ with which the advance ends of the conveyer-blades a¹ a⁷ are 75 aligned for feeding the undissolved material through said openings into the chamber F. The pocket or scoop f extends transversely between the shoulders or flanges f¹ f² and projects forwardly from the rear edge of the 80 opening e¹ towards the inner face of the shell A. This pocket or scoop serves to receive and hold the material fed to the chamber F, and as said pocket or scoop is elevated, the material therein falls downwardly by 85 gravity into the receptacle or chamber E.

The feeding chamber F, the pocket or scoop f, and the opening e¹ in the revoluble receptacle or chamber E form a particularly simple and efficient means for feeding the 90 undissolved material from the shell A to said revoluble receptacle or chamber E. My improved lixiviating apparatus may, however, be provided with a stationary receptacle or chamber for receiving the undissolved material and in that event, a different means for feeding the undissolved material into 95 said receptacle or chamber would be required. Such a modified construction of my invention is illustrated in Fig. 7, in which 100 A¹⁰ represents the inclosing shell for receiving the dissolvent liquid and the soluble material, B¹⁰ a stationary receptacle or chamber for receiving the undissolved material, and B¹¹ an additional receptacle or chamber 105 for receiving the material discharged from the first receptacle or chamber which preferably consists of a chute. The undissolved material is usually fed into the first receptacle or chamber B¹⁰ by one or more rotary 110 pockets a¹⁰ which are formed with open inner portions or ends and are secured to the inner face of the shell A¹⁰ within a feeding chamber a¹¹ provided at the upper end of 115 said shell A¹⁰. Suitable spiral conveyer-blades a¹² feed the material through the shell A¹⁰ into the sides of the pockets a¹⁰, and when said pockets are elevated above the receptacle or chamber B¹⁰, the material 120 therein feeds by gravity from their open inner portions or ends into said receptacle or chamber. The second receptacle or chamber B¹¹ preferably consists of a perforated revoluble cylinder provided with a conveyer-blade b¹⁰ which discharges the material from 125 130

the outer end of said receptacle or chamber. It is obvious, however that the receptacle or chamber B¹⁰ may conduct the material to any suitable feeding means, as an endless belt provided with buckets or pockets for receiving said material.

In the operation of the preferable form of my invention, the dissolvent liquid is discharged into one end of the inclosing shell A and the soluble material is fed into the opposite end of said shell. The dissolvent liquid passes slowly from compartment to compartment of the shell A towards the inlet-conduit or pipe B for the soluble material and escapes from said shell into the chamber D and the conduit or pipe d whence it may be conducted to any desired locality. The soluble material, together with any additional material simultaneously fed into the inclosing shell, is moved or conveyed in a direction opposite to that of the dissolvent liquid and any material not dissolved and carried backwardly by said liquid is fed into the feeding chamber F whence it is discharged into the receptacle or chamber E. The conveyer within the receptacle or chamber E continues the onward movement of the undissolved material until the same is discharged from said receptacle or chamber at the exterior of the shell A. As the material is passing through the receptacle or chamber E, the inlet-conduit or pipe C discharges the strong or fresh dissolvent material thereon for preventing the escape of any soluble material, and said liquid, together with any additional liquid mixed with the undissolved material and small particles of said material, escape through the perforations of said receptacle or chamber into the inclosing shell A and then pass into the feeding chamber F through the openings in the upper side of said feeding chamber. The liquid fed through the upper side of the feeding chamber continues its onward movement towards the chamber D, and the undissolved material fed through said side of the chamber F is again returned to the receptacle or chamber E.

The operation of my improved lixiviating apparatus will be readily understood upon reference to the foregoing description and the accompanying drawing, and, as considerable change may be made in the construction and arrangement of the component parts of said apparatus without departing from the spirit of my invention, I do not herein specifically limit myself to the exact construction and arrangement of the parts of said apparatus.

Having thus fully described my invention, what I claim as new and desire to secure by Letters Patent, is:—

1. A lixiviating apparatus comprising an inclosing shell, an inlet-conduit for the dissolvent liquid, means for mechanically feed-

ing the soluble material against the current of dissolvent liquid, and a receptacle for receiving the undissolved material from the feeding means, said receptacle extending into the inclosing shell and being located near the source of the dissolvent liquid for receiving the dissolvent liquid when fresh, the walls of the receptacle having perforations, substantially as and for the purpose specified. 76

2. A lixiviating apparatus comprising an inclosing shell, an inlet-conduit for the dissolvent liquid, means for mechanically feeding the soluble material against the current of dissolvent liquid, a receptacle for receiving the undissolved material from the feeding means, said receptacle extending into the inclosing shell and being located near the source of the dissolvent liquid, the walls of the receptacle having perforations, and means for returning the undissolved material washed through the perforations, to the receptacle, substantially as and for the purpose set forth. 75

3. A lixiviating apparatus comprising an inclosing shell, an inlet-conduit for the dissolvent liquid, means for mechanically feeding the soluble material against the current of dissolvent liquid, a receptacle for receiving the undissolved material from the feeding means, said receptacle extending into the inclosing shell and being located near the source of the dissolvent liquid, the walls of the receptacle having perforations, means for returning the undissolved material washed through the perforations, to the receptacle, and means for conveying the coarser undissolved material from the receptacle to the outside of the shell, substantially as and for the purpose described. 90 95

4. In a lixiviating apparatus, a shell, a spiral blade therein, a second blade arranged within said shell, the pitch thereof being opposite to that of the first blade, a second shell arranged within the first shell and within one of the spiral blades, means for transferring the material under treatment from the first shell into the second, and means in the second shell for moving the material therein, substantially as and for the purpose specified. 100 105 110

5. In a lixiviating apparatus, a shell, a spiral blade therein, a second blade arranged within said shell, the pitch thereof being opposite to that of the first blade and arranged to deliver the material to a portion of the shell intermediate of the ends thereof, a second shell arranged within the first shell and within one of the spiral blades, means for transferring the material under treatment from said intermediate portion of the first shell into the second, means in the second shell for moving the material therein, and an inlet-conduit for the dissolvent liquid, discharging into the second shell, 115 120 125 130

substantially as and for the purpose set forth.

6. In a lixiviating apparatus, a shell, a spiral blade therein, means for discharging soluble material into one end of said shell, means for advancing the material through the shell against the current of dissolvent liquid, means within the shell arranged to deliver the material in an opposite direction to a portion of the shell intermediate of the ends thereof, a second shell, means for transferring material from said intermediate portion of the first shell to the second, means for advancing the material through the second shell, the walls of the second shell having perforations, and means for returning to the first shell material discharged from the second shell through said perforations, substantially as and for the purpose described:

7. A lixiviating apparatus comprising a revoluble inclosing shell, an inlet-conduit or pipe for the dissolvent liquid, means for mechanically feeding the soluble material in the inclosing shell towards the inlet-conduit or pipe, a receptacle or chamber for receiving the undissolved material, and a pocket or scoop supported within the inclosing shell and revoluble therewith for feeding the undissolved material into the receptacle or chamber, substantially as and for the purpose specified.

8. A lixiviating apparatus comprising an inclosing shell, means for mechanically feeding the soluble material in the inclosing shell, a revoluble receptacle or chamber having a portion thereof arranged within the inclosing shell and provided with an inlet-opening, and a pocket or scoop fixed to the revoluble receptacle or chamber for feeding the undissolved material through said inlet-opening, substantially as and for the purpose set forth.

9. A lixiviating apparatus comprising a revoluble inclosing shell, an inlet-conduit or pipe for the dissolvent liquid, means for mechanically feeding the soluble material in the inclosing shell towards the inlet-conduit or pipe, a receptacle or chamber for receiving the undissolved material, a pocket or scoop supported within the inclosing shell and revoluble therewith for feeding the undissolved material into the receptacle or chamber, and a stationary chamber communicating with the inclosing shell for receiving the solution of said liquid and material, substantially as and for the purpose described.

10. A lixiviating apparatus comprising a revoluble inclosing shell, an inlet-conduit or pipe for the dissolvent liquid, means for me-

chanically feeding the soluble material in the inclosing shell towards the inlet-conduit or pipe, a receptacle or chamber having a portion thereof arranged within the inclosing shell for receiving the undissolved material, said receptacle or chamber having a portion of its wall perforated, and a pocket or scoop supported within the inclosing shell and revoluble therewith for feeding the undissolved material into the receptacle or chamber, substantially as and for the purpose set forth.

11. A lixiviating apparatus comprising a revoluble inclosing shell, an inlet-conduit or pipe for the dissolvent liquid, means for mechanically feeding the soluble material in the inclosing shell towards the inlet-conduit or pipe, a receptacle or chamber arranged within the inclosing shell for receiving the undissolved material, said receptacle or chamber having a portion of its wall perforated, means within the receptacle or chamber for feeding the undissolved material to the exterior of the inclosing shell, and means at the outside of said receptacle or chamber for feeding material in an opposite direction, substantially as and for the purpose described.

12. A lixiviating apparatus comprising a revoluble inclosing shell, an inlet-conduit or pipe for the dissolvent liquid, means for mechanically feeding the soluble material in the inclosing shell towards the inlet-conduit or pipe, a receptacle or chamber projecting within the inclosing shell for receiving the undissolved material, said receptacle or chamber being formed with an opening in its wall, and a pocket or scoop on the interior of the inclosing shell discharging within said opening, substantially as and for the purpose specified.

13. A lixiviating apparatus comprising a revoluble inclosing shell, an inlet-conduit or pipe for the dissolvent liquid, means for mechanically feeding the soluble material in the inclosing shell towards the inlet-conduit or pipe, rock-arms arranged on opposite sides of a vertical plane projected through the axis of the inclosing shell, and rollers secured to the opposite ends of the rock-arms for supporting said shell, substantially as and for the purpose specified.

In testimony whereof I have hereunto signed my name in the presence of two attesting witnesses, at Syracuse, in the county of Onondaga in the State of New York, this 23rd day of January 1897.

EDWARD N. TRUMP.
